CLAIM

The ornamental design for a receiver pin, as shown and described.

DESCRIPTION

FIG. 1 is a perspective view of a receiver pin showing our new design;

FIG. 2 is a top view of the design shown in FIG. 1;
FIG. 3 is a side view of the design shown in FIG. 1;
FIG. 4 is a bottom view of the design shown in FIG. 1;
FIG. 5 is a back view of the design shown in FIG. 1;
FIG. 6 is a side view of the design shown in FIG. 1;
FIG. 7 is a front view of the design shown in FIG. 1;

FIG. 8 is a perspective view of the receiver pin, wherein the clip is in the locked position;

FIG. 9 is a perspective view of a second embodiment of the receiver pin;

FIG. 10 is a top view of the design shown in FIG. 9;

FIG. 11 is a side view of the design shown in FIG. 9;

FIG. 12 is a bottom view of the design shown in FIG. 9;

FIG. 13 is a back view of the design shown in FIG. 9;

FIG. 14 is a side view of the design shown in FIG. 9;

FIG. 15 is a front view of the design shown in FIG. 9;

FIG. 16 is a perspective view of the receiver pin, wherein the clip is in the locked position;

FIG. 17 is a perspective view of a third embodiment of the receiver pin;

FIG. 18 is a top view of the design shown in FIG. 17;

FIG. 19 is a side view of the design shown in FIG. 17;

FIG. 20 is a bottom view of the design shown in FIG. 17;

FIG. 21 is a back view of the design shown in FIG. 17;

FIG. 22 is a side view of the design shown in FIG. 17;

FIG. 23 is a front view of the design shown in FIG. 17;

FIG. 24 is a perspective view of the receiver pin, wherein the clip is in the locked position;

FIG. 25 is a perspective view of a fourth embodiment of the receiver pin;

FIG. 26 is a top view of the design shown in FIG. 25;

FIG. 27 is a side view of the design shown in FIG. 25;

FIG. 28 is a bottom view of the design shown in FIG. 25;

FIG. 29 is a back view of the design shown in FIG. 25;

FIG. 30 is a side view of the design shown in FIG. 25;

FIG. 31 is a front view of the design shown in FIG. 25; and,

FIG. 32 is a perspective view of the receiver pin, wherein the clip is in the locked position.

The broken lines, which define the bounds of the claimed design, form no part thereof. The broken line environmental showing is for illustrative purpose only and forms no part of the claimed design.
